UNITED STATES PATENT OFFICE

THOMAS A. NOVOTNEY, OF JOHNSTOWN, PENNSYLVANIA, ASSIGNOR TO NATIONAL RADIATOR CORPORATION, OF JOHNSTOWN, PENNSYLVANIA, A CORPORATION OF DELAWARE

RADIATOR

Application filed April 7, 1930. Serial No. 442,122.

This invention is for an improvement in heating radiators, and is for a radiator especially designed to provide a relatively large radiating surface in a relatively compact space.

The tendency in room heating with steam and hot water systems is toward the provision of radiators built into the wall rather than setting out from the wall, these built-in 10 radiator units being disposed in a space through which the convective circulation of air may be readily induced. For instance, with such a wall unit the radiator itself is entirely concealed within the wall behind 15 paneling, which is open both near the floor and above the top of the radiating unit. Cold air is drawn in from the floor heated by circulation around the radiator unit and discharged through the openings at the top of 20 the panel above the radiator unit.

Inasmuch as the average room wall thickness is relatively small, it is necessary for the radiator units to be exceedingly compact and at the same time provide a great deal of surface 25 over which the air may circulate to be warmed. The present invention, which relates primarily to a cast metal unit, provides a radiator section which is exceedingly compact, which provides a relatively large heat 30 dissipating surface relative to the total overall dimensions of the section, and one which may be conveniently arranged in various ways with other sections to provide a compact heating unit of high efficiency.

35 The invention may be readily understood by reference to the accompanying drawings in which

Figure 1 represents a front elevation of a single section made in accordance with my 40 invention;

Figure 2 is a transverse vertical section in substantially the plane of line II-II of Fig. 1, but through an assembly of two units arranged face-to-face;

45 Figure 3 is a transverse section through a single radiator section, the section being substantially in the plane of line III-III of Fig. 1;

Figure 4 is a similar section substantially 50 in the plane of line IV-IV of Fig. 1;

Figure 5 is a similar section through either end of the unit in Fig. 1, as through the lines V-V; and

Figure 6 is a transverse section on a slightly larger scale through one end portion of one of 55 the radiator sections, in substantially the plane of line VI-VI of Fig. 1.

In the drawings I have shown each radiator section 2 as being provided with three parallel columns 2^a, 2^b and 2^c. These columns are 60 connected together at the center of the section by cross connections 3. The columns terminate in hollow end portions 4. The end portions are provided on each of the side faces of the sections with openings 6, as shown in 65 Fig. 5, having ground surfaces 7 for contact with adjacent sections. These openings have a very slight taper into which connectors or caps may be forced, the caps being used where the section is an outside section, and the connectors being used where the section is adjacent another section.

In each end wall of the portion 4 is an internally threaded opening 8 communicating with the interior space in the radiator. 75 The purpose of this opening is to provide for the insertion of a threaded nipple or threaded cap. Also, as shown in Fig. 6, the top of the upper portion 4 and the bottom of the lower portion 4 are each provided with an internally threaded opening 9 into which a screw plug or pipe may be screwed, depending upon whether this opening is to be closed or whether it is to be connected to another section or to a water or steam pipe. As thus arranged it will be seen that each of the end portions 4 has an opening at each end of the section, an opening in each side face of the section, and an opening in each edge face of the section. The openings 8 and 9 are intended for cooperation with threaded couplings or caps, while the openings 6 are intended for the insertion of force-fitted caps or nipples.

95 On each side face of each section is a series of laterally projecting fins, these fins being designated 10 on one side of the section and 11 on the other side of the section. These fins are equally spaced, but the fins 11 are staggered with reference to the fins 10, so that 100

each fin 11 lies in a plane half-way between two fins 10. These fins are cast integral with the radiator section, and project beyond the ends of the sections just the same as they project beyond the sides. It will be noted that the fins 10 and 11 project beyond the faces of the end portions 4 of the radiator, as clearly shown in Figure 2. By reason of this arrangement the fins of one section overlap the fins of an adjacent section, as shown in Fig. 2, and by reason of the staggered arrangement of the fins 10 with respect to the fins 11, the fins 10 of one section overlapping the fins 11 of the adjacent section lie half-way between the fins 11.

It will of course be understood by those skilled in the art that a cooling fin projecting a certain distance out from the prime heating surface will be efficient for warming the air circulating about the radiator, but that beyond this point any further extension of the fins adds little or nothing to the efficiency, and the metal so used is of practically no benefit. The arrangement shown in the present invention allows the fins to be the maximum width possible for the diameter of the water columns which may be used, and this is only possible by reason of the overlapping arrangement of the fins. Since the fins project from the edges of the radiator sections as well as from the wide side faces, it will be seen that the staggered arrangement permits the sections to be arranged in edge-to-edge relation with the fins at the edge of one section interfitting but staggered with relation to those of the adjacent section. It will be noted by reference to Fig. 1 that the fins at the edges project a substantial distance beyond the plane of the edges of the portions 4. This is evident from the projection lines A—A in Fig. 1. In Fig. 2 the distance which the fins project beyond the face of the portion 4 is readily seen by reference to the projection lines B—B.

By reason of this arrangement cast metal heating sections are provided with a minimum of thickness and a maximum heat dissipating area consistent with the amount of prime surface provided by the water spaces of the radiator. By this arrangement it is possible to make heat dissipating fins of a width sufficient to insure the greatest efficiency, and yet allow adjacent sections to be very compactly arranged. By reason of the arrangement of openings in the end portions of the radiator it is possible to effect various combinations of sections to get the greatest number of sections in a given limited space. For instance, two sections may be used in edge-to-edge relation, in which case the sections are connected by a coupling leading from one of the openings 8 in one section to a similar opening in the section above it, and the openings 6 are closed while the intake and outlet pipes may connect into the

openings 9. Also, as shown in Fig. 2, two sections may be arranged parallel in face-to-face relation, in which case communication between the sections is established through the openings 6, and the openings 8 and 9 can be connected with water or steam pipes or plugged, as the exigencies of given installations may require. Obviously, any number of sections may be arranged in this face-to-face relation, and one group of sections arranged in this way may be arranged in edge-to-edge relation above another group of sections arranged in the same way. The arrangement and disposition of the sections with relation to each other is governed entirely by the amount of radiating area required and the amount of space available for its accommodation. Since installations of this kind are well-known in the art and the manner of arranging different groups of sections is also well understood, I have not shown the various arrangements in detail, as the same will be readily understood by those skilled in the art.

It is desirable in a structure of this kind that the air be brought into intimate contact with the heating surface, wherefor it is necessary to have the fins closely spaced. The problem of casting the fins in an iron section and getting them close together is one that presents a considerable difficulty. In the present invention the fins are spaced sufficiently far on each side of the section to facilitate casting, but where they overlap with the fins of another section, as shown in Fig. 2, the space between the fins is broken up into relatively small passageways. The arrangement, not only, however, gives the effect of closely spaced fins, but also offers some impedance to the circulation of the air so that it does not flow over the heating surfaces too rapidly.

While I have stated the radiator as adapted for use where it is built into a wall, it may also be used with various enclosures, in unit heaters and wherever else compact sections are desired or necessary.

I have described a present preferred embodiment of my invention, but the invention is not restricted to the specific construction and arrangement herein particularly described, and may be otherwise embodied within the scope of the following claims.

I claim:

1. A radiator section comprising a prime heating portion having a plurality of columns and an end portion at each end of the section with which the columns of the prime portion communicate, a series of regularly spaced laterally projecting fins on one face of the radiator section, the ends of said fins terminating in a plane beyond the plane of the side faces of the end portions of the radiator, and a similar series of fins on the other

side face of the radiator section staggered with respect to the first series of fins.

2. An integral radiator section of cast metal comprising a prime heating surface and a terminal portion at each end of the section, the terminal portions being of greater width and thickness than the intermediate portion, and a series of transverse integral fins on the intermediate portion, those 5 on one side of the section being staggered with relation to those on the other, the fins projecting at both the edges and the faces of the section beyond the dimensions of the end portions.

15 3. A radiator section adapted to be arranged in face-to-face relation with another similar section, or in edge-to-edge relation with another similar section, having heat radiating fins thereon projecting beyond the 20 boundaries of the main portion of the radiator at both the edges and faces of the section, the fins on one face of the section being staggered half-way between the fins on the other side of the section.

25 4. In a radiator having a plurality of sections with overlapping heat radiating fins thereon, end portions for each section having connector openings at the end of the said portion, in each side face of the said portion, 30 and in each edge face of the section.

5. A radiator section comprising a main body portion having an end portion at each end thereof, an opening at each end of the said portion, an opening in each side face of 35 the end portion of the section, and an opening in each edge surface of the end portion of the section.

6. A radiator section comprising a main body portion having an end portion at each 40 end thereof, a threaded opening at each end of the section, an opening in each side face of the end portion of the section, and an opening in each edge surface of the end portion of the section, said section having a 45 series of heat radiating fins on one-half thereof and another series of fins on the other half thereof, the fins of the first series being alternated with respect to those of the second series, the overall dimensions of the radiator 50 section through the fins being greater than the overall dimension of the radiator at any other point whereby the fins project beyond the confines of the radiator and may be arranged in overlapping relation with similar 55 fins of an adjacent radiator section.

In testimony whereof I have hereunto set my hand.

THOMAS A. NOVOTNEY.
